[57] **CLAIM**

The ornamental design for a hand grip for torque applying tools, as shown and described.

DESCRIPTION

FIG. 1 is an elevational view showing one side of a hand grip for torque applying tools made pursuant to my present design;

FIG. 2 is a view showing one end thereof;

FIG. 3 is a view similar to FIG. 1 but at right angles thereto;

FIG. 4 is a view showing the opposite end thereof; and FIG. 5 is a view similar to FIG. 1 showing the opposite side thereof.

The dotted lines in the drawing are disclosed for illustrative purposes only and form no part of the claimed design.

Fig. 1.

Fig. 2.

Fig. 3.
